FAN CONSTRUCTION

Charles L. Moorman, Millington, Ill., assignor to
Union Asbestos & Rubber Company, a corpora-
tion of Illinois

Application June 28, 1945, Serial No. 602,047

5 Claims. (Cl. 230—129)

1

This invention relates to fan construction and more particularly to fans for use in railway refrigerator cars and the like to maintain a circulation of air therethrough.

One of the objects of the invention is to provide a fan construction which occupies a minimum space for a given capacity and which can conveniently be mounted below the surface of the lading racks in a car.

Another object is to provide a fan construction whose housing can be utilized as a beam to assist in supporting the lading racks or to form a part of the lading supporting surface. To this end the housing is preferably made substantially rectangular to provide a flat upper surface and has its sides reinforced to provide the necessary strength.

Still another object is to provide a fan construction in which air is guided into and out of the housing and the housing is reinforced by vertical fins on the housing at the opposite sides of the inlet and outlet openings.

Still another object is to provide a fan construction in which the fan blades are shrouded to increase their efficiency. In a preferred construction, the fan blades are widened at their ends and are partially encircled by curved shrouding means which extends over the widened end portions of the blades.

The above and other objects and advantages of the invention will be more readily apparent from the following description when read in connection with the accompanying drawings, in which—

Figure 1 is a partial plan view of a fan construction embodying the invention;

Figure 2 is a section on the line 2—2 of Figure 1;

Figure 3 is a side elevation looking into the outlet openings; and

Figure 4 is a partial section on the line 4—4 of Figure 3.

The fan construction comprises an elongated housing which is preferably formed of sheet metal rectangular in section having a flat horizontal top 10 and vertical sides 11. A base 12 on the top 10 and vertical sides 11 may be welded or otherwise suitably secured to the sides 11 and preferably extends beyond the sides as seen in Figure 2. One of the sides 11 is formed with a series of inlet openings 13 and the other side is formed with a series of outlet openings 14 which are staggered with respect to the inlet openings 13.

In order to reinforce the housing and to guide the air properly into and out of the outlet openings vertical fins 15 which may conveniently be

punched out from the sides 11 to be integral therewith, are formed on the opposite sides of the housing adjacent the opposite edges of the inlet and outlet openings. The fins preferably taper upwardly as seen in Figure 2 and serve both to provide guiding channels for the air flow and to stiffen and strengthen the sides of the housing.

When the housing is installed in a railway car, the upper flat surface 10 thereof preferably lies flush with the upper surface of the lading racks in the car so that the housing forms in effect a part of the lading supporting surface. The lading racks may also, if desired, be secured to the housing to be supported thereby. In this way the entire fan mechanism is mounted in a relatively small space below the lading supporting surface in the car and either forms a part of or assists in supporting the lading racks.

Within the housing an elongated shaft 16 is journaled on spaced pillow blocks 17, the shaft preferably extending completely through the housing. The shaft is adapted to be driven, by any suitable means shown, as a driving pulley 18 on one end thereof to be connected to a driving pulley of any desired type. The shaft supports within the housing a plurality of sets of fan blades 19 which extend substantially radially outward from the shaft. As shown in Figure 2 the blades are carried by blocks 21 which are adapted to be clamped to the shaft. It will be noted that each of the sets of fan blades lies opposite an outlet opening 14 so that the inlet openings 13 communicate with the spaces between the sets of fan blades.

As best seen in Figures 3 and 4, the fan blades are relatively narrow adjacent the shaft and flare outwardly to wider portions at their tips. The widened outer portions of the blades are partially enclosed by a shroud 22 in the form of a relatively thin sheet metal strip which as seen in Figure 2 extends from the upper end of an outlet opening 14 around the tips of the fan blades to the base of the housing substantially at the vertical center of the fan. Throughout at least a portion of its length each of the strips 22 is bent inwardly, as indicated at 23, to overlie the widened tip portions of the blades partially to enclose them.

In operation the shaft 16 may be driven to rotate the fan blades so that they will draw air in through the inlet openings 13 and discharge it tangentially through the outlet openings 14. Air entering through the inlet openings flows axially into the sets of fan blades and is caused to flow along the blades and tangentially out of the outlet openings as will be understood. The

shrouds 22 and the inwardly extending portions 23 thereof greatly increase the efficiency of the fan blades so that relatively large fan capacity will be provided in a relatively small space. These shroud strips are simple and inexpensive to construct and can easily be installed in the housing being held therein by friction alone or by any desired type of fastening means.

While one embodiment of the invention has been shown and described in detail, it will be understood that this is illustrative only and is not intended as a definition of the scope of the invention, reference being had for this purpose to the appended claims.

What is claimed is:

1. A fan construction for railway cars and the like comprising an elongated housing having staggered inlet and outlet openings in its opposite sides, a shaft extending longitudinally through the housing, a plurality of sets of substantially radial fan blades carried by the shaft in register with the outlet openings, and the housing being formed with outwardly extending fins at the opposite sides of the inlet and outlet openings to guide the air and to reinforce the housing.

2. A fan construction for railway cars and the like comprising an elongated housing having staggered inlet and outlet openings in its opposite sides, a shaft extending longitudinally through the housing, a plurality of sets of substantially radial fan blades carried by the shaft in register with the outlet openings, the sets of fan blades being open at their ends for flow of air axially into them from the inlet openings and for tangential discharge through the outlet openings and integral upwardly tapering fins extending outwardly from the housing at the opposite sides of the inlet and outlet openings to guide the air and to reinforce the housing.

3. A fan construction for railway cars and the like comprising an elongated housing substantially rectangular in section adapted to be supported on the floor of the car, the housing being formed in its opposite sides with a plurality of staggered inlet and outlet openings, an elongated shaft extending through the housing, a plurality of sets of substantially radial fan blades on the

shaft opposite the outlet openings, and outwardly extending fins on the housing at the opposite sides of the inlet and outlet openings to guide the air and to reinforce the housing.

4. A fan construction for railway cars and the like comprising an elongated housing substantially rectangular in section adapted to be supported on the floor of the car, the housing being formed in its opposite sides with a plurality of staggered inlet and outlet openings, an elongated shaft extending through the housing, a plurality of sets of substantially radial fan blades on the shaft opposite the outlet openings, and curved shrouds in the housing partially encircling the sets of fan blades throughout approximately half of their circumference to leave the outlet openings open and extending inwardly at their edges over the outer end portions of the fan blades.

5. A fan construction for railway cars and the like comprising an elongated housing substantially rectangular in section adapted to be supported on the floor of the car, the housing being formed in its opposite sides with a plurality of staggered inlet and outlet openings, an elongated shaft extending through the housing, a plurality of sets of substantially radial fan blades on the shaft opposite the outlet openings, each of the fan blades being relatively narrow adjacent the shaft and flaring out to wider portions at their outer ends, and curved shrouds in the housing partially encircling the sets of fan blades throughout approximately half of their circumference and extending inwardly at their edges to overlie the wider portions of the fan blades.
